UNITED STATES PATENT OFFICE

156,245

DESIGN FOR A TOY AUTOMOBILE MOVING VAN

Benjamin Josefsberg, Forest Hills, N. Y.

Application August 30, 1947, Serial No. 141,130

Term of patent 3½ years

(Cl. D34—15)

To all whom it may concern:

Be it known that I, Benjamin Josefsberg, a citizen of the United States, residing at Forest Hills, in the State of New York, have invented a new, original, and ornamental Design for a Toy Automobile Moving Van, of which the following is a specification, reference being had to the accompanying drawings, forming part thereof, in which:

Figure 1 is a top plan view of a toy automobile moving van embodying my new design;

Figure 2 is a side elevational view of the toy automobile moving van shown in Figure 1;

Figure 3 is a front elevational view of the toy automobile moving van shown in Figure 2; and

Figure 4 is a rear elevational view of the toy automobile moving van shown in Figure 2.

The side not shown is substantially like the side shown in Figure 2.

What I claim is:

The ornamental design for a toy automobile moving van, as shown and described.

BENJAMIN JOSEFSBERG.
